UNITED STATES PATENT OFFICE.

HENRY R. GORDON, OF DETROIT, MICHIGAN.

ATTACHMENT TO BAKERS' OVENS.

SPECIFICATION forming part of Letters Patent No. 256,813, dated April 11, 1882.

Application filed October 26, 1881. (No model.)

To all whom it may concern:

Be it known that I, HENRY R. GORDON, of Detroit, in the county of Wayne and State of Michigan, have invented an Improvement in 5 Bakers' Ovens, of which the following is a specification.

The nature of this invention relates to certain new and useful improvements in attachments to bakers' ovens, and it is especially applicable to those of the rotary-oven class. Great annoyance is experienced by the baker in the use of the rotary ovens, caused by the deposit of ashes and dust upon the material being baked at such time as the fire is being replenished or enlivened by shaking the grates, and thus stirring up and throwing off from the fire a large quantity of ashes, which fills the oven and deposits upon the baking-shelves, the draft not being sufficient to carry it off; and it is 15 the object of my invention to do away with this annoyance; and to that end the invention consists in the peculiar construction and operation of an adjustable sliding arch to cover over the furnace or furnaces at such times as 20 may be desired, all as more fully hereinafter set forth.

In the accompanying drawing, which forms a part of this specification, and which fully represents the application of my attachments 30 in sectional perspective, A represents the walls of the furnaces of a rotary oven, within which are constructed the furnaces B and draft-openings a, of the ordinary construction. The upper portion of the oven, in which is arranged 35 the rotating shelves and reel, I do not show, as they form no part of invention.

In the use of the ordinary oven of this class fire is made in the furnaces B, the smoke and products of combustion from which pass down 40 the passages a to the chamber C below the floor of the oven, and thence to the chimney-flue D, and as these fires are kept alive the entire day, generally, it becomes necessary to replenish by adding more fuel through the 45 proper furnace-door, or to enliven the fire by shaking the grates to remove the ashes which accumulate over the grates and obstruct the draft, and in doing this a greater or lesser amount of ashes is disturbed, which flies up 50 through the open top of the furnaces into the

oven and lodges upon the crackers or other material being baked upon the rotary reel, there not being sufficient draft to carry it all down through the draft-openings. This renders the material being baked more or less 55 dirty upon the outer surfaces, while it necessitates a frequent cleaning of the interior of the oven. To avoid these difficulties I arrange within the oven an arch, E, for each furnace, composed preferably of sheet metal, open at 60 the bottom and at the front end, the opposite end being closed. Where there are two furnaces, as shown in the drawing, these arches are connected together by one or more bars, F, and they are arranged to slide within suitable tracks or ways, G, running lengthwise of the oven, as shown, said arches being advanced or retracted by means of an endless chain or cable, I, attached to the bar F and running over pulleys b, which are operated by means 65 of a crank-handle and shaft, J.

Immediately over the furnace-door I provide an air passage or flue, K, adapted to be closed by a slide or door, L.

When I desire to replenish or enliven the 75 fire I turn the crank-handle J, so that the arches I will be drawn forward, their open ends abutting against the inner face of the front wall of the furnace, while they entirely close over the top of each furnace. I then open the 80 draft-dampers, with which the ovens are ordinarily supplied, and open the doors or slides L and close the lower doors. This admits of a passage of air through the flues K to and beneath the arches and over the top of the fire. 85 Then in raking or replenishing the fire the dust which is thrown off, being confined by the arches, is directed to the draft-openings a, down which it passes into the chamber C, where it deposits, the smoke and gases passing on 90 up the chimney-flue. I then close the doors L and retract the arches E to the rear of the oven, which allows the furnaces to discharge their heat directly into the oven. It will be seen that by the use of these adjustable arches 95 I entirely avoid the annoyance referred to, while at the same time I provide a means for regulating the heat of the oven, as it can readily be seen that the arches may be drawn over so as to partially close the furnaces or en- 100

tirely, if desired, allowing the oven to be heated then merely by such heat as shall be derived from the radiation through the arches.

What I claim as my invention is—

- 5 1. A baker's oven the furnaces of which are provided with adjustable sliding arches E, substantially as and for the purposes set forth.
2. An oven, and in combination with the furnaces B thereof, provided with adjustable sliding arches E, the draft-openings K, and outlets a, substantially as and for the purposes specified.
- 10 3. An oven, and in combination with the fur-

naces B thereof, the sliding arches E, adapted to be operated by the chain I, pulleys b, and 15 crank-shaft J, substantially as described.

4. In a baker's oven, and in combination with the furnace B thereof, having a draft-opening, K, and outlet a, the arch E, provided with one open and one closed end, and adapted to be moved to cover or partly cover the furnace, substantially as described.

HENRY R. GORDON.
